LAMINATED GUERIN BOX

Charles F. Derbyshire, Chula Vista, Calif., assignor to
Rohr Aircraft Corporation, Chula Vista, Calif., a corporation of California

Application May 18, 1953, Serial No. 355,711

3 Claims. (Cl. 113—44)

This invention relates to an improved construction of a machine of the type shown in United States patent to Guerin, No. 2,190,659 for forming sheet metal to the shape of a die. In the method of forming disclosed in this patent, a mass of soft rubber is positioned in a hollow box which is attached to the plunger of a power press. The sheet metal workpiece is placed upon a shaped die which is supported on a metal pedestal which has the same shape as the opening in the bottom of the box and fits closely within the opening. As the box descends the rubber applies an increasing pressure to the workpiece which causes it to bend and progressively conform to the surface of the die.

It has been the practice, as illustrated in the above patent, to make the top and sides of the box of a single piece of metal, such as a casting or forging, or to fasten the sides to the top of the box by welding. During the last few years this method has been used for the forming of increasingly larger workpieces and thicker sheet metal with an attendant increase in pressure developed in the rubber. The rubber presses against the sides of the box and develops a shear force which tends to shear the sides from the top of the box and the pressure against the sides induces cantilever type bending stresses in the box which tend to fracture it. It is a main object of this invention to provide a box construction for the rubber which is free of such cantilever induced bending stresses and shear stress.

It is a further object of the invention to provide a sliding connection between the top and sides of the box so that the sides can expand and contract independently of the top under the outward force applied by the rubber.

A further object is to provide a deep box of great strength made up of a plurality of steel laminations each of which is a single piece of metal and the several laminations being welded together into a unitary structure.

A further object is to provide means for sealing the joint between the sides and top of the box which will prevent the rubber under pressure from creeping between the sides and top and escaping from the area in which it is confined thus causing failure of the press.

Another object is to provide guide pins for guiding the box into proper registry with the pedestal which supports the die or dies.

Further objects will become apparent as the description of the forming press proceeds. For a better understanding of the invention reference is made to the accompanying drawings, in which:

Figure 1 is a view, partly in section on line 1—1 of Figure 3, of a portion of a forming machine embodying the invention;

Figure 2 is a top view of the lower portion of the machine of Figure 1 with the forming die and workpiece removed;

Figure 3 is a top view of a portion of the machine and;

Figure 4 is a sectional view showing the means for securing two portions of the machine together.

On a stationary base 10 is secured by any suitable means

2

(not shown) a metal plate 11 to the ends of which are attached a pair of square blocks 12 which have attached thereto smooth cylindrical guide pins 13 whose upper ends 14 are of substantially hemispherical shape. At its center plate 11 has secured to it a generally rectangular shaped pedestal 15, the vertical sides and top of which are machined smooth. Pedestal 15 supports the forming die 16 and metal sheet 17 which is to be formed to the contour of the curved top face 18 and side face 19 of the die. For simplicity only a single die and workpiece have been shown but it will be understood that a plurality of dies of different shapes may be set on pedestal 15 and a corresponding number of metal sheets bent simultaneously to the shapes of these dies.

The movable portion of the forming machine comprises the ram 20 of a press, the ram being vertically reciprocated in a known manner by means of a fluid actuated piston (not shown). Attached to ram 20 is a flat plate 21, the plate having along its opposite edges a plurality of slots 22 through which bolts 23 pass, the shanks of the bolts entering threaded holes in the ram.

Attached to plate 21 (see Figs. 3 and 4) by a plurality of Allen head screws 24 is a containing box wall 25 in a manner to permit sliding contact between the wall and plate. This is secured by drilling a plurality of holes 26 in the plate and counterboring each hole to provide a shoulder 27 against which a washer 28 disposed under the head of the screw is seated. Each hole 26 is of substantially greater diameter than the diameter of the shank of screw 24 so that a sliding connection is provided between box wall 25 and plate 21 as the wall expands and contracts slightly under the high internal pressure to which it is subjected. The wall shown has straight ends 29 while the front and rear faces 30 are convexly curved.

35 The box wall is composed of a plurality of strong steel laminations welded together, as shown, and welded to the sides of the wall are a pair of lugs 31 which have guide bushings 32 adapted to engage and slide along guide pins 13 as ram 20 descends. The bottom lamination 33 is machined to provide a smooth vertical face 34 of the same shape as the top of pedestal 15 so that face 34 has close telescopic engagement with the pedestal.

40 A body 35 of resilient, flowable rubber is packed into the box wall 25, the bottom face of the rubber being a substantial distance above the bottom of wall 25, as shown.

The rubber is of approximately 60 Shore test and preferably consists of several horizontal laminations. To prevent the rubber from being squeezed between the plate 21 and the top lamination and thereby separating portions of the box in which the rubber must be confined, a continuous sealing member 36 in the form of an angle iron has a vertical leg in contact with the inside of the top lamination and a horizontal leg in contact with the bottom face of plate 21, as shown in Figures 1 and 3. Member 36 may be secured to body 25 by any suitable means such as screws (not shown). The several parts of the machine, except rubber body 35, are preferably made of strong steel. Since each lamination is designed to counteract the total outward pressure of the portion of the rubber body lying within it, the number of laminations can be increased to any desired extent.

65 To operate the machine the ram 20 is raised to the position shown, die 16 is placed on pedestal 15 and a metal sheet 17 of aluminum, brass or other flexible metal placed on the die. Ram 20 is then slowly lowered and as vertical face 34 of the box wall commences to slide along the vertical face of pedestal 15, the rubber 35 commences to press sheet 17 against die 16 and to bend the sheet. This bending continues as the ram descends, the bottom face of the rubber no longer remaining flat but shaping progressively as the sides of the sheet are bent down into conformance with the sides 19 of the die and

the middle of the sheet is bent into conformance with the shaped top 18 of the die. Should any of the rubber enter, for example, the extremely small space between the face 34 and the end of pedestal 15 at the left in Figure 1, the force exerted on pedestal 15 and plate 11 would tend to move these members toward the right on base 10. This would cause the right hand portion of face 34 to rub against the end of pedestal 15 at the right as the ram continued to descend. In forming many parts on the same die this repeated rubbing together of these surfaces would gradually wear them away. Such sidewise motion of pedestal 15 with reference to flange 25 is effectively prevented by the cooperative action of the guide pins 13 and bushings 32 which maintain pedestal 15 substantially central within opening 34. After the workpiece is fully formed, the ram is raised to its top position, the formed workpiece removed from the die and other metal sheets formed in the same manner.

It has been the practice, as illustrated in the above patent, to make the box wall 25 and plate 21 which enclose the rubber as a one piece forging or casting with the result that the wall acted as a beam anchored at its upper end. Under the high outward pressure of the rubber, large bending stresses of the cantilever type are set up in the flat plate in the region where it joins the wall and have caused boxes to fracture in this region so that they could not be used again. Also large shear stresses were set up in the wall where it joins the plate, which further weakened the structure. By this invention such bending and shear stresses are entirely avoided since applicant's box wall 25 is free to move in and out along plate 21 as it expands and contracts under the stresses applied internally by the rubber.

This invention may be embodied in other forms or carried out in other ways without departing from the spirit or essential characteristics thereof. The present embodiment of the invention is therefore to be considered as in all respects illustrative and not restrictive, the scope of the invention being indicated by the appended claims, and all changes which come within the meaning and range of equivalency of the claims are intended to be embraced therein.

Having thus described my invention, what I claim as new and useful and desire to secure by Letters Patent is:

1. A device for forming a sheet metal blank to the form of a shaped die by pressure from the vertical ram of a press comprising; a flat plate composed of rigid metal, a plurality of spaced apart detachable fasteners securing the top of said plate continually against the bottom of the ram, said plate being provided with a plurality of spaced apart vertical bores; a rigid box wall depending

from said plate, said wall and plate forming a pocket or recess, the top of said wall having a plurality of threaded openings in alignment with said bores; a plurality of headed screw fasteners having their shanks disposed in said bores and having their threaded lower ends screwed into said threaded openings to hold the top face of said box wall continually in contact with the bottom face of said plate, the shanks of said headed fasteners being of substantially smaller diameter than said bores to thereby permit limited movement of the top face of said box wall along the bottom face of said plate; a body of resilient flowable material disposed in said recess, the top of said body being in engagement with said plate and the body having an exposed lower surface at a level above the bottom of said wall; a stationary base under said wall; a pedestal projecting up from said base and having a substantially horizontal top face adapted to support the die and sheet metal blank resting on the die, said box wall and body of resilient material when in raised position being well spaced from the die to allow ready access to the blank for its rapid placement on and removal from the die; the lower portion of the wall being of substantially the same shape and size as the pedestal so as to fit directly in telescoping relation therewith upon lowering the press ram whereby lowering the ram causes said body of yielding material to be compressed and restrained against outward expansion by said plate and wall and will first press said blank against said die by engagement of said lower exposed surface therewith and upon application of further pressure will shape said blank along the die.

2. A forming device as claimed in claim 1; in which said box wall is composed of a plurality of steel laminations welded together and said headed fasteners are in threaded engagement with the top lamination only.

3. A forming device as claimed in claim 1; in which said box wall is composed of a plurality of steel laminations welded together and the portion of the wall which is the same shape and size as the pedestal consists of a smooth vertical face formed on only the bottom lamination.
